UNITED STATES PATENT OFFICE.

JOSEPH HIRTH, OF ST. LOUIS, MISSOURI.

REFLECTOR ATTACHMENT FOR LANTERNS.

SPECIFICATION forming part of Letters Patent No. 353,678, dated December 7, 1886.

Application filed March 10, 1886. Serial No. 194,673. (No model.)

To all whom it may concern:

Be it known that I, JOSEPH HIRTH, a citizen of the United States, residing in the city of St. Louis, State of Missouri, have invented 5 a certain new and useful Improvement in Reflector Attachments for Lanterns, of which the following is a full, clear, and exact description.

On the accompanying drawings, Figure 1 is a side elevation or edge view of a reflector constructed and applied according to my invention; Fig. 2, a back view of the reflector and its attachment devices; and Fig. 3, a plan of Fig. 2, partly broken away, like letters of reference denoting like parts in all the figures.

15 *a* represents a reflector, to the back of which are soldered or otherwise fixed the two parallel and upright portions *b* of a wire or other metal attachment, said portions *b* extending below the reflector *a*, and projecting forward 20 at their lower ends in a bracket, *b'*, arranged horizontally at right angles, or thereabout, with the upright portions *b* of the wire or other metal attachment, which is bent round in an upward direction at the front end of the bracket 25 *b'*, so as to form a curved hooked catch, *b''*, as shown. The upper ends of the upright portions *b* of the wire or other metal attachment are extended forward horizontally and constitute arms *b³*, which are inclined from each 30 other in the same plane and terminate in hooks *b⁴*, facing each other.

In attaching the reflector *a* to the lantern *B* the base of the lantern is placed on the bracket portion *b'*, between the hooked catch *b''* and upright portions *b* of the wire or other metal attachment, the arms *b³* of which are at the same time separated or diverged radially to the upright portions *b* until the lantern *B* is properly 35 adjusted on bracket portion *b'*, when the arms *b³*, which, on being diverged, have been brought into a state of torsional tension or springiness,

owing to the slight twisting of the vertical portions *b*, will rebound, and their hooks *b⁴* closing onto and embracing the upright air-tubes *c* (or other suitable appendages) of the lantern 45 *B*, the reflector *a* is thereby securely attached to the lantern *B*.

To the upper part of the back of the reflector *a* is fixed a spring-hinged wire clamp, *d*, which extends downward over the reflector *a* and normally tends to spring back against the lantern. On pulling out the clamp *d* from the reflector *a* it can be passed over the dash-board *e*, Fig. 1, of a carriage or wagon, and, springing back thereon, securely fastens the reflector 55 *a*, with the attached lantern *B*, to the carriage or wagon.

I am aware that detachable reflector attachments for tubular and other lanterns are not new, and I do not desire to claim the same, 60 broadly. The advantages of my improvement are, however, that, owing to the lower securing-bracket, *b' b''*, engaging with the base of the lantern and acting with the upper securing-arms, *b³*, the reflector, while it is easily detached, is held rigidly in position, and is prevented from rattling, or either horizontal or lateral motion.

I claim—

The combination, with a lantern-reflector, 70 *a*, of a wire or other metal attachment composed of upright portions *b*, horizontal bracket *b'*, hook or catch *b''*, adapted to engage the base of the lantern, arms *b³*, and hooks *b⁴*, substantially as shown, and for the purpose described. 75

In testimony whereof I have affixed my signature, in presence of two witnesses, this 6th day of March, 1886.

JOSEPH HIRTH.
